UNITED STATES PATENT OFFICE.

LOUIS W. RICE, OF NEW YORK, N. Y., ASSIGNOR TO BERNARD RICE'S SONS, INC., OF NEW YORK, N. Y.

DESIGN FOR A METAL BORDER STRIP OR SIMILAR ARTICLE OF MANUFACTURE.

Application filed February 14, 1924. Serial No. 8,636. Term of patent 7 years.

To all whom it may concern:

Be it known that I, LOUIS W. RICE, a citizen of the United States, residing at 325 Fifth Avenue, New York city, in the county of New York and State of New York, have invented a new, original, and ornamental Design for a Metal Border Strip or Similar Article of Manufacture, of which the following is a specification, reference being had to the accompanying drawing, forming part thereof.

The figure shown in the drawing is a plan view of my ornamental border strip which is adapted for use on tableware generally and is made and sold as an independent article of manufacture.

I claim:

The ornamental design for a metal border strip or similar article of manufacture as shown and described.

Signed at the city of New York, county of New York and State of New York, this 12th day of February, 1924.

LOUIS W. RICE.
